United States Patent Office.

CHARLES E. MOORE, OF NEW YORK, N. Y.

Design No. 4,993, dated June 13, 1871.

DESIGN FOR A LONG COMB.

The Schedule referred to in these Letters Patent and making part of the same.

To all whom it may concern:

Be it known that I, CHARLES E. MOORE, of the city, county, and State of New York, have invented a new Design for a Long Comb; and I do hereby declare that the following is a full, clear, and exact description of the same, reference being had to the accompanying drawing forming part of this specification, and in which—

Figure 1 is a perspective view of a long comb of my design.

Figure 2 is a plane projection representing the comb as it would appear if straightened, and showing the profile of the teeth.

Similar letters of reference indicate corresponding parts in both figures.

The novelty in this design relates to the teeth, which are provided along the whole length of the

comb, and the bases of which are all on the same line, *a a*, extending straight or directly along the back *A*, but which are made shorter at and for some distance from the middle of the length of the comb, so that their points present a line, *b c c d d*, the middle portion *b* and end portions *c c* of which are straight and parallel with each other, but the middle portion *b* is recessed and unites with the end portions *c c* by two, more or less, abrupt bends, *d d*.

What I claim as my invention, and desire to secure by Letters Patent, is—

The design for a long comb, herein represented and described.

CHARLES E. MOORE.
